UNITED STATES PATENT OFFICE.

REX G. AVERILL, OF MANSFIELD, OHIO, ASSIGNOR TO THE OHIO BRASS COMPANY, OF MANSFIELD, OHIO, A CORPORATION OF NEW JERSEY.

ANTICOUPLING MECHANISM.

Application filed February 7, 1922. Serial No. 534,669.

To all whom it may concern:

Be it known that I, REX G. AVERILL, a citizen of the United States of America, residing at Mansfield, in the county of Rich-
5 land and State of Ohio, have invented cer-
tain new and useful Improvements in Anti-
coupling Mechanism, of which the follow-
ing is a specification.

My invention relates to car couplers, and
10 more particularly to means for preventing,
at will, the coupling of cars provided with
an automatic coupler when bumped to-
gether.

I have shown my invention as applied to
15 a particular style of automatic coupler, but
I do not wish it understood that the inven-
tion is applicable to this style of coupler
only.

In the accompanying drawing:—

20 Fig. 1, shows a top plan view of my in-
vention, combined with a pair of coupler
heads in coupled relation.

Fig. 2, shows a top plan view of my in-
vention, combined with a pair of coupler
25 heads and operating to prevent the coupling
of the heads.

Fig. 3, is a top plan view of a single cou-
pler head provided with my anti-coupling
30 invention shown in inoperative position in
full line and in operative or anti-coupling
position in dotted line.

Fig. 4, is a front view of a coupler head
35 with my anti-coupling invention applied
thereto, as in Fig. 3.

Fig. 5, is a side view of my anti-coupling
invention applied to a coupler head and
40 shown in two positions—operative position
in dotted line, and inoperative position in
full line.

45 As shown, I employ a coupler head hav-
ing a body 1, a hook 2 to interlock with a
hook on a co-operating coupler head when
their faces 3 are brought into engagement,
as shown in Fig. 1. The hook is pivotally
50 mounted within the body by the pin 4.

Secured to the top face of the body, 1,
55 are two lugs 5—5, and hinged to the lugs
by means of a pin 6, is an angular shaped
anti-coupling member 7, which can be ro-
tated about the pin 6 and engage the face
60 3 of the coupler, as shown in dotted line in
Figs. 3, 4 and 5, to prevent two counter part
heads from coupling.

The thickness of the anti-coupling mem-
65 ber 7, is considerably greater than the dis-

tance between the face 8 of the hook and
the face 3 of the coupler head, and there-
fore, the couplers are prevented from cou-
pling when one or both of the members 7
are in operative position.

It often happens in handling cars about
70 coal mines and excavation work, that it is
desirable to bump two or more cars together
without inter-coupling, and when such is the
case, the anti-coupling member 7 can be
75 thrown into operative position as shown on
head No. 1 of Fig. 2, and the coupler hooks
will not interlock. The same result will
also happen if the member 7 on head No. 1
is thrown into operative position, or if both
80 members on the heads are operated.

Having shown and described my inven-
tion, and set forth the objects, and how used,
I claim:—

1. A coupler comprising a body member,
85 a projecting member to interlock with a cor-
responding member on a counter-part cou-
pler to connect the couplers and a hinged
member mounted on the body member to be
moved into position to be engaged by the
90 counter-part coupler to prevent interlock-
ing of the projecting means.

2. The combination with a car coupler
95 provided with a body member and means to
inter-lock with means on a counter-part cou-
pler for the purpose of connecting the cou-
plers, of hinged means mounted on the body
member to be moved into position to be en-
gaged by the counter part coupler to pre-
100 vent inter-locking of projecting members.

3. The combination with a pair of co-
operating car couplers of hinged means on
one coupler to be moved, at will, into posi-
105 tion to engage means on the other couplers
to prevent connecting the couplers.

4. The combination with a pair of co-
operating car coupler heads of hinged means
on each and movable into position to pre-
110 vent the connecting of the couplers.

5. The combination with a pair of co-
operating car couplers of hinged means on
each coupler to co-operate with each other
to prevent the connecting of the couplers.

6. A coupling mechanism comprising a
body member and means to inter-lock with
each co-operating coupler for the purpose
of connecting the couplers, an L shaped
member hinged to the body member to be
rotated into one position to prevent the cou-
pler connecting with the co-operating cou-
115

pler and to be rotated into another position to permit the coupler to connect with the co-operating coupler.

7. The coupling mechanism comprising a body member and means to inter-lock with a co-operating coupler for the purpose of connecting the couplers, a member hinged to the body member to be rotated into one position to prevent the coupler connecting with the co-operating coupler and to be rotated into another position in which the coupler connects with the co-operating couplers.

8. A coupling mechanism comprising a body member and means to inter-lock with a co-operating coupler for the purpose of connecting the couplers, a hinged member to prevent at will, the connecting of the couplers, comprising a member movable into one position to prevent the connecting of the

couplers and movable into another position to permit the connecting of the couplers, means mounted on the coupler and means connecting the last means and the movable member in rotatable relation for the purpose described.

9. A coupling mechanism comprising a body member, connecting means to inter-lock with a co-operating coupler, a face on the body member to engage a face on the co-operating coupler when in coupled relation, with means on the body to be moved, at will, into position, to engage the face on the body member and face of the co-operating coupler to prevent the inter-locking of the connecting means.

In testimony whereof I affix my signature.

REX G. AVERILL.
